UNITED STATES PATENT OFFICE

JOSEPH H. HENDRICK, OF OAKLAND, KENTUCKY

CUTTING DEVICE

Application filed April 7, 1930. Serial No. 442,311.

This invention relates to a cutting device.

One of the objects of my invention is the construction of a simple and efficient device for cutting metal either square off or on any angle, owing to how the metal is placed on the device; the device will cut metal roofing of all kinds, metal siding, etc.

Another object of my invention is the construction of a device wherein the shear blade or knife is mounted on a spindle, which spindle is mounted within two metal bushings, and these bushings are carried by rear block-like auxiliary members of the device.

With the foregoing and other objects in view, my invention comprises certain novel constructions, combinations and arrangements of parts as will be hereinafter fully described, illustrated in the accompanying drawings, and more particularly pointed out in the appended claims.

In the drawings:

Figure 1 is a perspective view of a device constructed in accordance with the present invention.

Figure 2 is a longitudinal central sectional view of the device.

Figure 3 is an enlarged view taken on line 3—3, Figure 2, and looking in the direction of the arrows.

Figure 4 is a view in elevation of one of the metal bushings.

Figure 5 is a perspective view of one of the spacing plates.

Figure 6 is a perspective view of the spindle.

Referring to the drawings by numerals, 1, 1 designates the two long horizontal primary members of the device against the inner faces of which are secured metal blade strips 2.

40 The securing of strips 2 is preferably by means of screws 3, Fig. 2. Against the under face of the primary members 1, I place front block-like auxiliary members 4 and rear block-like members 5.

45 A rear spacing plate 6 and a front spacing plate 7 are placed between the primary members 1 and the auxiliary members 4 and 5, with bolts 8 extending through all of the members securing the same together. These plates or shims 6 and 7 are always of the

same thickness as the pivoted shear blade 9. By changing the thickness of the spacing plates, a larger width or a smaller width shear blade may be used, as conditions require. Therefore, in a true sense, the spacing plates perform the function of spacing the parts apart as shown in the drawings and also are of an "adjustable" nature to accommodate different width shear blades.

In the rear auxiliary members 5, I place transversely a pair of metal bushings 10, which are each provided on its inner end with an annular flange 11. This flange 11 keeps the metal bushing from sliding outwardly. The flange 11 bears against the inner face of the auxiliary member 5 in each instance. A spindle 12 with a squared center 13 and round end portions 14 is employed; the round ends 14 are journaled in the metal bushings 10 with the squared portion 13 seated in a similarly constructed aperture of the depending portion 15 of the shear blade 9. In other words, the shear blade is "keyed" upon the spindle so that when the shear blade is raised and lowered, it rotates the spindle within the metal bushings 10. The shear blade is provided with a suitable grip 16, which is grasped by the operator while the device is being used.

75 My cutting device will give entire satisfaction in the cutting of metal, such as sheet metal or in the cutting of other materials.

70 The bolts 8 fasten the primary and auxiliary members together with the central longitudinally extending opening, formed by the spacing plates, the right width for the particular shear blade being used. The blade strips 2 co-operate with the shear blade for an accurate cutting action upon the material being cut in each instance.

90 While I have described the preferred embodiment of my invention and illustrated the same in the accompanying drawings, certain minor changes or alterations may appear to one skilled in the art to which this invention relates, and I, therefore, reserve the right to make such changes or alterations as shall fairly fall within the scope of the 95 appended claims.

What I claim is:

1. In a device of the class described, the combination of spaced parallel primary members, auxiliary members beneath said primary members, metal strips secured to the inner faces of said primary members, metal bushings extending transversely through said auxiliary members, said metal bushings provided with annular flanges on their inner 5 ends positioned below the lower edges of said blade strips and against the inner faces of said auxiliary members, a spindle journaled in said bushings, said spindle provided with a central squared portion and a shear blade 10 mounted on said central squared portion between said metal strips and primary members.
2. In a device of the class described, the combination of two spaced parallel primary 20 members, metal blade strips secured to the inner faces of said primary members, a pair of front block-like auxiliary members and a pair of rear block-like auxiliary members against the under faces of said primary 25 members and at their ends, detachable spacing plates between said blade strips and primary members, a pair of metal bushings in said rear auxiliary members and provided on their inner ends with means for preventing 30 the displacement of said spindles off said auxiliary members, a spindle rotatably mounted in said metal bushings, and a shear blade provided at its inner end with a depending portion fixedly mounted upon said 35 spindle, substantially as shown and described.

In testimony whereof I hereunto affix my signature.

JOSEPH H. HENDRICK.
